UNITED STATES PATENT OFFICE.

HENRY M. GREEN, OF LOS ANGELES, CALIFORNIA, ASSIGNOR, BY MESNE ASSIGNMENTS,
TO C. M. O'LEARY.

LONGITUDINAL FIBROUS PACKING FOR PLUNGER PUMPS.

Application filed July 28, 1924, Serial No. 728,653. Renewed October 3, 1927.

This invention relates to plunger pumps and more especially to so called "deep well" pumps.

An object is to provide an improved and 5 stationary packing system. In this connection an object is to provide a unit system of up-standing, fibrous strands in a stationary support and to provide means, simple and practical, to divert sand particles from the 10 packing.

More objects and advantages will be made manifest in the following specification of an embodiment of apparatus of my invention shown in the accompanying drawing; it being 15 understood that other modifications, variations and adaptations may be resorted to within the spirit of the invention and the scope thereof as here claimed.

The invention consists of apparatus achieving 20 the objects.

Fig. 1 is a longitudinal section of the pump. Fig. 2 is a top end view of a packing unit.

Fig. 3 is a longitudinal section of a packing unit.

25 Fig. 4 is an end view of a packing ferrule. Fig. 5 is an elevation of the ferrule.

Screwed onto the lower end of the packing barrel B² is a collar C in which is screwed a bottom barrel B³ which has on its bottom end 30 a coupling D having a ring seat 7 for a packing ring 8. A gland 9 screws into coupling D and receives the upper end of a standing-valve barrel B⁴ which has a shoe S from which depends the anchor or suction pipe A.

35 Normally standing in and on the shoe S is any suitable type of standing valve instrumentality V, here shown as of three story type, that is, having three valves 10. The standing valve sleeve 11 is embraced by the 40 packing 8 and this stops sand from settling down around the structure V and keeps it free so that it can be readily lifted out.

Included in the stationary elements of this 45 pump is the plunger packing, one unit of which is shown in detail in Figs. 2-3. Each unit includes a base ring R peripherally recessed at 14 and rough faced so as to bite into applied ends of hanks or plaits 12 of fiber strands forming the packing P. To clinch 50 the bottom or butt end of the packing in base

ring R a ferrule 15 is jambed on the packing to press it to its seat in recess 14. Preferably the upper ends of the plaits or hanks of fiber packing are ravelled out to form a brush-like end P' creating a mat for sediment 55 to pack in and provide a dense packing body. Any number of packing units is strung along the packing barrel B² and each has a spacing jacket J to prevent the base rings R from shifting in the barrel. A set of units is held 60 between couplings, as C.

A distinctive feature of this pump is that the packing barrel (B²) is packed for its full effective length. Another feature is that the elongated fiber packing is stationary and lies 65 lengthwise with the stroke and is therefore not cross-wiped. Again the length of the plunger shell 33 is such as to at all times cover the main packing P.

What is claimed is:

1. In a plunger pump, a working barrel for a plunger, a unit system of packing lining fixed in the barrel from end to end, each unit consisting of longitudinally lying fibrous strands forming a cylinder in which the 75 plunger slidably works, and spacing jackets holding each unit against longitudinal movement along the barrel.

2. In a plunger pump, a barrel, and an up-standing, fibrous packing cylinder having 80 longitudinal strands and presenting an internal bearing surface, held stationary in the barrel and in which the pump plunger works.

3. In a plunger pump, a packing device consisting of a cylinder of longitudinally lying strands ravelled out at one end to form a mat or brush to collect sediment.

4. A plunger pump packing device comprising an outer sleeve-like jacket, a base ring, a cylinder of longitudinal strands presenting an internal bearing surface and having the upper end ravelled out, and a retaining ferrule clinching the opposite end of the strands in place.

5. In a plunger pump, relatively slidable 95 plunger and barrel means, an elongated sleeve of fibrous packing having longitudinally extending strands, and means for preventing end movement of the packing.

HENRY M. GREEN.
